UNITED STATES PATENT OFFICE.

JOHN E. MUHLFELD, OF SCARSDALE, NEW YORK, ASSIGNOR TO LOCOMOTIVE
PULVERIZED FUEL COMPANY, A CORPORATION OF DELAWARE.

APPARATUS FOR FEEDING PULVERIZED FUEL.

1,243,753.

Specification of Letters Patent.

Patented Oct. 23, 1917.

Application filed December 31, 1913, Serial No. 809,696. Renewed March 27, 1917. Serial No. 157,847.

To all whom it may concern:

Be it known that I, JOHN E. MUHLFELD, of Scarsdale, in the county of Westchester and State of New York, have invented a certain new and useful Improvement in Apparatus for Feeding Pulverized Fuel, of which improvement the following is a specification.

My invention relates to means for delivering pulverized fuel from a storage receptacle to one or more supply conduits through which it is conveyed to a desired point of delivery, and its object is to provide an apparatus of such self-contained character which shall be of simple and inexpensive construction and readily applicable to and removable from operative position, and by which a continuous supply of pulverized fuel may be maintained, in desired and determined quantities and without liability to clogging or obstruction of the discharge passage of the storage receptacle.

The improvement claimed is hereinafter fully set forth.

25 In the accompanying drawings: Figure 1 is a vertical section through the lower portion of a pulverized fuel storage receptacle, illustrating an embodiment of my invention; Fig. 2, a transverse section through the same, on the line *a a* of Fig. 1; Fig. 3, a section, similar to Fig. 1, showing a structural modification; Fig. 4, a transverse section through the same, on the line *b b* of Fig. 3; and, Fig. 5, a partial similar section, showing a further structural modification.

40 My invention is herein exemplified in connection with a pulverized fuel storage receptacle, 1, which may be of any desired form and dimensions, and which, not being, in and of itself, of my present invention, need not be herein at length set forth. Referring first to Figs. 1 and 2, in the practice of my invention, I provide, at the bottom of the fuel receptacle, one or more conveyer channels or pockets, 1^a, any desired number of which may be applied, and two being shown in this instance. A discharge opening, 1^b, is formed in the bottom of each of the conveyer channels, and a conveyer, of 45 any suitable and preferred form, various forms of which are known in the art, is fitted to operate over the discharge opening in such manner as to carry pulverized fuel to said opening. The conveyer is preferably, as shown, of the screw type, and com-

prises a helical blade, 2, which is formed upon or secured to a shaft, 2^a, journaled in bearings, 1^c, in the opposite ends of the conveyer channel. A longitudinally extending baffle plate, 1^d, may, if desired, be fixed in the channel, above the conveyer, to prevent tendency to the packing of fuel above the discharge opening. Upon rotation being imparted to the conveyer, in any suitable manner, pulverized fuel from the storage receptacle, which drops by gravity into the conveyer channel, will be moved longitudinally in the latter and carried to the discharge opening, 1^b, thereof. The surplus of pulverized fuel which passes over the discharge opening and is not taken up by the measuring wheel, is forced back to the receptacle by the wedging action of the conveyer against the front, the conveyer thus acting both to feed fuel to the lower discharge opening and to agitate and circulate it in the receptacle.

45 A measuring wheel, 3, the periphery of which is divided into a plurality of transverse grooves or recesses, 3^a, is secured upon a shaft, 4, which is mounted in bearings, 5^a, on a casing, 5, within which the measuring wheel rotates and fits comparatively closely. The shaft, 4, may be rotated as found most suitable under conditions of installation. A delivery conduit, 6, located below the casing, 5, communicates therewith through an opening, 6^a, in its top, located immediately below the measuring wheel, 3, and leads to a desired point of delivery, as a boiler furnace or a chamber in communication therewith. It will be seen that a measured quantity of pulverized fuel will be carried from the conveyer channel to the delivery conduit, in each revolution of the measuring wheel, its quantity being dependent upon the width of face of said wheel, and the depths of its peripheral grooves. While only one discharge opening and one measuring wheel are shown in connection with a conveyer channel, two or more may be applied, in the discretion of the constructor, the number thereof being principally dependent upon the length of the conveyer channel and the desired rapidity of feed to the fuel.

50 Figs. 3 and 4 illustrate a structural modification embodying the essential operative principle of the apparatus above described, and differing structurally therefrom in the

particular that the shafts of the measuring wheels, 3, three of which are shown on each shaft, in this instance, are located in the same vertical planes as, and parallel with, 5 the conveyer shafts, 2^a, instead of being set at a right angle thereto, as in the former case. The shafts of the measuring wheels may, as shown, be rotated by spur gears, 4^a, fixed thereon and engaging similar gears, 10 2^b, on the conveyer shafts.

As shown in Fig. 5, the shafts of the measuring wheels are located relatively to the conveyer shafts similarly to those of Figs. 3 and 4, but all the measuring wheels of 15 each conveyer channel discharge into a single delivery conduit instead of into independent conduits, as in Figs. 3 and 4.

The fuel feeding apparatus above described may be varied as to form, dimensions, and number of elements of each conveyer channel or pocket of the fuel storage receptacle, in accordance with operative conditions and installation requirements, without departure from the spirit and character 20 features of my invention.

I claim as my invention and desire to secure by Letters Patent:

1. In an apparatus for feeding pulverized fuel, the combination, with a fuel storage receptacle having closed ends and a discharge opening in its bottom, intermediate of its ends, of a fuel delivery conduit extending below the discharge opening, means for conveying fuel through the receptacle across 30 said opening, and means for transferring fuel, in measured quantities, from said opening to the fuel delivery conduit.

2. In an apparatus for feeding pulverized fuel, the combination, with a fuel storage

40 receptacle having closed ends and a discharge opening in its bottom, intermediate of its ends, of a conveyer adapted to move fuel longitudinally across said opening, a fuel delivery conduit extending below said opening, a casing interposed between, and communicating with, said opening and said conduit, and a measuring wheel fitted to rotate in said casing.

3. In an apparatus for feeding pulverized fuel, the combination, with a fuel storage 45 receptacle having closed ends and a discharge opening in its bottom, intermediate of its ends, of a screw conveyer fitted to rotate in the receptacle, above said opening, and to move fuel across it, a fuel delivery conduit extending below said opening, a casing interposed between, and communicating with, said opening and said conduit, and a peripherally recessed measuring wheel fitted to rotate in said casing. 60

4. In an apparatus for feeding pulverized fuel, the combination, with a fuel storage receptacle having closed ends and a discharge opening in its bottom, intermediate of its ends, of a screw conveyer fitted to rotate in the receptacle, above said opening, and to move fuel across it, a baffle plate extending longitudinally above said conveyer, a fuel delivery conduit extending below the discharge opening, a casing interposed between, and communicating with, said opening and said conduit, and a peripherally recessed measuring wheel fitted to rotate in 65 70 said casing.

JOHN E. MUHLFELD.
